UNITED STATES PATENT OFFICE.

JOSEF BRANDSTETTER, OF CHICAGO, ILLINOIS.

BOTTLE CORKING AND CAPPING MACHINE.

1,402,713.

Specification of Letters Patent. Patented Jan. 3, 1922.

Application filed October 12, 1921. Serial No. 507,391.

To all whom it may concern:

Be it known that I, JOSEF BRANDSTETTER, citizen of the United States, residing at Chicago, in the county of Cook and State 5 of Illinois, have invented certain new and useful Improvements in a Bottle Corking and Capping Machine; and I do hereby declare the following to be a full, clear, and exact description of the invention, such as 10 will enable others skilled in the art to which it appertains to make and use the same.

My invention relates to means for affixing closures to bottles and in one aspect aims to provide a convenient and easily operable machine which can be used with equal facility either for stopping bottles with corks or for affixing closure caps to the mouths of bottles. For this purpose, my invention aims to provide a machine in 20 which the same plunger and plunger-operating mechanism can be employed with equal facility for both of the said purposes, aims to provide an arrangement which can speedily be interchanged as to such purposes without using any tools, and aims to 25 keep the special parts for each of these purposes out of the way when the machine is used for the other purpose. Furthermore, it aims to provide easily manipulated means 30 for adjusting the machine to bottles of varying heights and for supporting the bottles in proper alinement with the closure-affixing portions of the mechanism.

In a more particular aspect, my invention 35 aims to provide an easily operated bottle corking machine which will facilitate the inserting of the corks, which will effectively compress the entering end of each cork before presenting the same to the mouth of the 40 bottle, which will automatically retract the cork guiding and compressing means as soon as the cork has been inserted to a predetermined extent, but which will prevent an undesirable slamming during the said 45 retraction. Furthermore, it aims to gage the extent of insertion of the cork automatically from the mouth end of the bottle irrespective of the length of the cork, and aims to facilitate the alining of the cork 50 guide with the cork-inserting plunger.

In another of its more detailed aspects, my invention aims to provide a bottle closing machine having a head adjustably mounted to adapt the same to bottles of 55 varying heights, and aims to provide sim-

ple means for keeping this head in proper operative position regardless of the height at which it is disposed. It also aims to provide this head both with a cork inserting plunger and means for actuating the plunger; aims to provide a movably mounted cork compressing guide yieldingly supported by the head, and aims to provide a cap-affixing head adapted to be secured to the same plunger when the machine is to be 60 used in connection with sealing caps. Still further and more detailed objects will appear from the following specification and from the accompanying drawings, in which— 65

Fig. 1 is an elevation of a machine embodying my invention showing the same with a bottle positioned for inserting a cork into its neck.

Fig. 2 is an enlarged and fragmentary 75 vertical section taken through the axes of the supporting stem and of the plunger of Fig. 1 and showing the parts as they appear when the cork is being inserted.

Fig. 3 is a fragmentary horizontal section taken along the correspondingly numbered line in Fig. 2 and showing the operating connection between the shaft of the handle and the plunger.

Fig. 4 is an elevation somewhat similar 85 to Fig. 1, but showing the machine as it appears when it is to be used for affixing a sealing cap to a bottle.

Fig. 5 is a central and vertical section through the lower end of the plunger when 90 the cap-affixing head is attached to the same as shown in Fig. 4.

In the embodiment of the drawings, the machine of my invention includes a base 1 having a top portion on which the bottle 95' may be set and having a substantially semi-circular guard 2 adapted to center a bottle 3 in predetermined position. Supported by the base 1 is a standard or riser 4 which extends through a vertical bore in a cross-head 5, this cross-head being clamped to the stem 4 at any desired height by a screw 6 having a handle end affording considerable leverage. The cross-head 1 also has another vertical bore having its axis spaced from 100 that of the stem 4 by a distance corresponding to the spacing between the axis of the said standard and the axis of the bottle 3. Extending slidably through this second vertical bore is a plunger 7 equipped on one 105

side with a series of teeth 8 affording a rack for engaging a pinion 9, which pinion is pivoted on the cross-head 5 on a horizontal axis and which has a handle 10 fastened to 5 the same, so that the plunger can be moved up and down by using the handle 10 to rotate the pinion 9. This plunger alines with the axis of a bottle set on the base concentric with the guard, the cross-head being 10 kept in the proper direction for thus overhanging the base by having the tip of the screw 6 enter a groove 31 in the riser. The cross-head 5 has a downward extension 11 terminating in a lower arm 12 which 15 also is bored to have the standard 4 extend through the same and which acts as a support for a spiral compression spring 13. This compression spring continuously exerts an upwardly directed pressure on the 20 upper one of two vertically spaced arms 14 and 15 which are slideable on the stem 4 and which are both fastened to a tubular cork guide 16. This cork guide is desirably made of brass and integral with the arms 14 and 25 15, which arms together with the tubular guide form the guide member. It also preferably has a main bore which tapers downwardly and which has its upper end larger in diameter than the normal size of the 30 corks which are to be used with the bottles, while its lower end is contracted to a diameter corresponding to (or slightly smaller than) that of the neck of the bottle. The cork guide 16 also has a downwardly flaring 35 extension 17 at its lower end which is cupped out substantially as shown in Fig. 2, so that it will readily seat on the mouth of the bottle to center the bottle with respect to the cork guide. 40 In using my machine as above described for affixing a cork to a bottle 3, I first clamp the cross-head 5 to the standard 4 at a height which will cause the cap 17 of the guide to clear the top of the bottle, thereby permitting 45 the ready insertion and withdrawal of the bottles which are to be corked. Next, I swing the cross-head out of alinement with the plunger 7, (this being done while the plunger is raised clear of the top of the guide 50 by suitably turning the handle 10) and drop a cork 18 into the upper end of the guide 16, the cork being desirably moistened in advance so as to facilitate the compressing of the same. I then swing the cork guide 55 into position for alining with the bottle and the plunger, after which I turn the handle so as to move the plunger downward and force the cork 18 into the neck of the bottle. In doing this, the tapering 60 bore of the guide 16 compresses the cork as the latter is being forced downward within the guide, and the friction of the cork while being compressed causes the movement of the plunger to force the guide downwardly 65 against the resistance of the spring 13. Con-

sequently, the upper portion 17 of the guide is forced into engagement with the mouth of the bottle before the cork reaches the bottle, thereby effectively centering the mouth of the bottle regardless of variations 70 in the shape or height of the bottle. As the movement of the plunger is continued, the latter then forces the cork 18 into the neck of the bottle. However, as soon as the top of the cork clears the lower end of the tapering main bore of the guide 16 or reaches the position shown in dotted lines in Fig. 2, the friction of the cork on the guide is released and the spring 13 immediately returns the guide member to the raised position shown in Fig. 1, thereby leaving ample room for the ready withdrawal of the bottle, and also signaling to the operator that the movement of the handle is to be discontinued. The movement of the handle is 85 then reversed so as to raise the plunger entirely above the top of the guide, after which the guide member is swung to one side upon its pivotal mounting on the standard 4 for inserting a fresh cork and the operation is 90 repeated with the next bottle.

By employing a spring in this manner for yieldingly supporting the guide I automatically adjust the guide for variations in the heights of the bottles, so that the operator 95 does not need to pay any attention to these variations within reasonable ranges, and I also facilitate the insertion and withdrawal of the bottles. However, an undue compression of the spring might cause an undesirable slamming action on the machine 100 during the raising of the guide member, hence I desirably provide a spacer tube 22 surrounding the riser portion within the spring but shorter than the normal length 105 of the spring, so that this tube limits the compressing of the spring. Likewise, since the cup 17 engages the mouth of each bottle and since the compression of the spring is automatically released whenever the top of 110 the cork reaches the upper end of the bore of the cup, the extent of insertion of the cork is automatically gaged from the top of the bottle. I therefore secure a uniform stopping of the bottles regardless of variations 115 in the lengths of the corks. To expedite the alining of the tubular cork guide with the plunger whenever a fresh cork has been inserted, I preferably provide means for limiting the return swinging movement of the 120 guide member about the standard 4, as by providing this member with a finger 21 adapted to engage the part 11 of the cross-head member as shown in Fig. 2.

When the machine is to be used for affixing closure caps of the kind comprising metal caps lined with cork, I swing the cork guide out of the way as shown in Fig. 4 and attach a cap-affixing head 19 to the lower end of the plunger 7 by means of a thumb 130

screw 20. Then I set the bottle in position as before, slip a loose cap over its mouth and depress the plunger by rotating the handle 10 in the usual manner. By thus employing 5 the same bottle support, plunger and plunger-actuating mechanism also for affixing sealing caps, I provide a machine which is equally adaptable regardless of the kind of the bottle closures which are to be used, the 10 change being made instantly and without the use of tools by merely manipulating the thumb screw 20.

Furthermore, it will readily be seen from the drawings that by loosening the handled 15 screw 6, I can readily adjust my machine for bottles of widely varying heights, and it will also be seen from the drawings that the entire arrangement is simple, inexpensive and easily manipulated. To avoid an 20 excessive dropping of the plunger 7 I desirably terminate the rack 8 somewhat below the top of the plunger as shown in the drawings. However, while I have illustrated and 25 described my invention in a desirable embodiment, I do not wish to be limited to the details of the construction and arrangement as here disclosed, it being obvious that these might be modified in many ways without departing from the spirit of my invention or 30 from the appended claims. Neither do I wish to be limited to such a twofold use of the machine of my invention, it being obvious for example that the cork-affixing arrangement as above disclosed could be employed 35 equally well if the machine were not provided with a cap-affixing head for attachment to its plunger.

I claim as my invention:

1. A combined bottle capping and corking machine including a plunger having a detachable cap-affixing head, a cork guide movable into and out of a position in which the plunger may be projected through the guide after the head has been detached, and 45 yielding means permitting limited downward movement of the cork guide.
2. A combined bottle capping and corking machine comprising a support arranged for holding a bottle, a plunger movable upon 50 the support in axial alinement with the bottle, a cap-affixing head attachable to the plunger, and a cork guide mounted on the support for movement both longitudinally and transversely of the axis of the bottle, the 55 cork guide including a bore through which the plunger can force a cork, and means for limiting the said transverse movement of the guide in one direction to a position in 60 which the said bore is in axial alinement with the bottle.
3. A bottle stopper comprising a base for supporting a bottle, a standard having a head overhanging the base, a vertically movable plunger carried by the said head in substantially axial alinement with a bottle supported by the base, and a tubular stopper guide pivoted upon the riser for movement 65 transversely of the axis of the plunger, the 70 said guide being cupped at its lower end for centering itself upon the mouth of the bottle, and yielding means normally holding the said guide above the mouth of the bottle.
4. An appliance as per claim 1, in combination with a cap affixing socket adapted to be secured to the lower end of the plunger when the stopper guide is moved out of its normal position about its pivotal mounting, whereby the same plunger can be used in 75 capping a bottle supported on the same base.
5. A bottle stopper comprising a base for supporting a bottle, a standard having a head overhanging the base, a vertically movable plunger carried by the said head in substantially axial alinement with a bottle supported by the base, and a tubular stopper guide pivoted upon the riser for movement 80 transversely of the axis of the plunger, the said guide being cupped at its lower end for 85 centering itself upon the mouth of the bottle, and cooperating means upon the head and guide for limiting the pivotal movement of the guide in one direction.
6. A combined bottle capping and corking 90 machine comprising a support arranged for holding a bottle, a plunger movable upon the support in axial alinement with the bottle, a cap-affixing head attachable to the plunger, a cork guide mounted on the support for 95 movement both longitudinally and transversely of the axis of the bottle, the cork guide including a bore through which the plunger can force a cork, and spring means associated with the guide and resisting 100 movement thereof longitudinally of the said axis toward the bottle by the frictional engagement of the cork with the guide.
7. A combined bottle capping and corking machine comprising a support arranged for 105 holding a bottle, a plunger movable upon the support in axial alinement with the bottle, a cap-affixing head attachable to the plunger, a cork guide mounted on the support for movement both longitudinally and 110 transversely of the axis of the bottle, the cork guide including a bore through which the plunger can force a cork, and means for limiting the said transverse movement of the guide in one direction to a position in 115 which the said bore is in axial alinement with the bottle.
8. A bottle stopper comprising a base for supporting a bottle, a standard having a head overhanging the base, a vertically movable plunger carried by the said head in substantially axial alinement with a bottle supported by the base, and a tubular stopper guide pivoted upon the standard for movement 120 transversely of the axis of the plunger and cupped at its lower end for centering itself upon the mouth of the bottle, the said head and stopper guide having relatively engage- 125

able portions for limiting the movement of the guide in one direction about its said pivotal mounting to a position in which the said cupped portion is in axial alinement with the plunger.

9. A bottle corking machine comprising a base, a standard carried thereby and having a head overhanging the base, a plunger vertically slideable through the head, and a stopper guide supported by the standard and having a vertical cork-feeding bore and mounted for movement transversely of the plunger.

10. A bottle corking machine comprising a base, a standard carried thereby and having a head overhanging the base, a plunger vertically slideable through the head, and a stopper guide supported by the standard and having a vertical cork-feeding bore and mounted for movement transversely of the plunger, and single means for simultaneously adjusting the height of the head and the stopper guide above the base, and a spring associated with the mounting of the stopper guide and yieldingly supporting the latter.

11. A bottle corking machine comprising a base, a riser carried thereby, a head adjustably mounted on the riser and overhanging the base and having an integral arm extending below the head proper, a spring surrounding a portion of the riser and supported by the said arm, a stopper guide pivoted upon the riser and supported by the spring, and a plunger extending vertically through the head and adapted to extend through a bore in the stopper guide when

the latter is swung to a predetermined position about its pivotal mounting.

12. A bottle corking machine comprising a base, a riser carried thereby, a head adjustably mounted on the riser and overhanging the base and having an integral arm extending below the head proper, a spring surrounding a portion of the riser and supported by the said arm, a stopper guide pivoted upon the riser and supported by the spring, and a plunger extending vertically through the head and adapted to extend through a bore in the stopper guide when the latter is swung to a predetermined position about its pivotal mounting, the stopper guide having a finger engaging the said arm to determine the said position.

13. A bottle corking machine comprising a base, a riser carried thereby, a head adjustably mounted on the riser and overhanging the base and having an integral arm extending below the head proper, a spring surrounding a portion of the riser and supported by the said arm, a stopper guide pivoted upon the riser and supported by the spring, and a plunger extending vertically through the head and adapted to extend through a bore in the stopper guide when the latter is swung to a predetermined position about its pivotal mounting, and means interposed between the said guide and arm for limiting the downward movement of the guide against the resistance of the spring.

Signed at Chicago, Illinois, October 6th, 1921.

JOSEF BRANDSTETTER.
